UNITED STATES PATENT OFFICE.

CLARENCE WHITE, OF DENVER, COLORADO.

UNLOADER FOR CENTRIFUGAL MACHINES.

1,202,936.

Specification of Letters Patent.

Patented Oct. 31, 1916.

Application filed November 21, 1914. Serial No. 873,420.

To all whom it may concern:

Be it known that I, CLARENCE WHITE, a citizen of the United States, residing at Denver, in the county of Denver and State of Colorado, have invented new and useful Improvements in Unloaders for Centrifugal Machines, of which the following is a specification.

My invention is an improvement in centrifugal machines and pertains particularly to apparatus for unloading the centrifugal and to the control and adjustment of this apparatus.

The object of the invention is to facilitate ease of operation of the unloading, rendering it possible for the operator to have perfect control with one hand of all the necessary functions and movements of the unloader leaving the other hand free to manipulate the control of the centrifugal machine.

A further object of the invention is to provide means for removing material from the screen of a centrifugal machine consisting of a reciprocating fluid motor mounted in connection with the centrifugal, a cleaning plow to be operated by the motor and a single manual device to turn the motor and the plow on their vertical axis and control the application of fluid power to the motor to raise and lower the plow.

The invention consists of the novel construction and arrangement of parts together with the novel method of operation and will be more fully described and set forth in the following specification and claims, and illustrated in the accompanying drawings in which—

Figure 1 is a vertical section through a centrifugal machine and the unloader attached thereto. Fig. 2 is a front elevation of the unloader. Fig. 3 is a plan view of the unloader mounted as shown in section in Fig. 1. Fig. 4 represents an enlarged transverse section through the control valve, showing the four way plug in position. Fig. 5 is an enlarged partial section of the control valve, showing the four way plug in position. Fig. 6 is an enlarged partial section of the manifold mounted on the upper cylinder head.

In the drawings like numerals indicate like parts.

1 is the casing of a centrifugal machine, 55 2 the screen or basket thereof and 3 a pul-

ley wheel driving a shaft 4 to revolve the basket 2. Mounted on the curb 5 of the casing is a support 6 extending out over the upper opening 7 of the basket 2. Set to turn in the bearing 8 and extending vertically through the support is a reciprocating fluid motor having the pressure cylinder 9, the piston 10 and piston rod 11. The lower cylinder head 12 is of heavy construction and provides bearing surface for engagement with the bearing surface 8 of the support, as well as suitable bearing surface 13 in which the piston rod 11 moves. The piston rod is prevented from turning in the cylinder by a multi-sided guide rod 14 suspended in the center line of the cylinder from the upper cylinder head 15 to which it is rigidly attached. The upper portion of the piston rod 11 is hollow to accommodate the guide rod 14 and the opening in the guide plate 16 which is keyed to or formed in the upper end of the piston rod conforms with the sides of the guide rod.

A plow or paddle 17 with a renewable tip 18 is attached rigidly to the lower end of the piston rod 11 and is designed to conform with the size and general requirements of the screen or basket 2. With the cylinder of the motor, the piston rod, and the plow operating as a unit about their vertical center line, free to swivel in the support 6, the plow 17 can be swung to or from the screen on which is deposited the material to be discharged through the bottom opening of the centrifugal.

Referring to the drawings Fig. 1 illustrates the piston and plow in the uppermost position, being a section along the line 1—1 of Fig. 2. Fig. 2 shows a front elevation of the unloader removed from the centrifugal, showing one form of plow attached to the piston rod. Fig. 3 shows a top plan view of the unloader mounted on a centrifugal machine, outlining diagrammatically the openings of the centrifugal machine and its basket.

Fluid power for raising or lowering the piston and plow may be taken from any suitable supply providing sufficient pressure. This is received into a special double manifold 19, Figs. 1, 2 and 6, rigidly attached to the top of the upper cylinder head 15, from which point it is carried through the pipe 20 to the control valve 21, Figs. 1, 4 and 5. A pipe 22 leads from this valve to

the top of the cylinder and another pipe 23 is connected to the bottom of the cylinder. An exhaust or outlet pipe 24 carries the discharge fluid back through the other side of the manifold 19. It will be observed that the various pipes and the valve structure are rigidly secured to and practically form a unit with the motor.

A lever 25 connected by trunnions 26 to the sides of motor, Figs. 1 and 3, is arranged to rest on top of the support 6 and provides means through said trunnion for turning the motor about its vertical axis on the support. The lever 25 is in direct alignment with the valve stem 27 of the valve 21 and is provided with a central longitudinal bore 28, Fig. 1. The grip 29 on the outer end of said lever operates the control valve 21 by means of a valve stem extension 30, inside of said bore 28, to which it is keyed and which is provided on its other end with a slotted socket 31 to fit the stem proper 27.

A four way cock is used in a control valve. Its construction and use will be apparent from the details illustrated in Figs. 1, 4 and 5. In these views Fig. 1 shows the relation between the valve and the general motor structure illustrating in dotted lines the position of the control lever in its locked position; Fig. 4 is a section through the valve and valve plug along the line 4-4 of Fig. 5, showing the four way feature; and Fig. 5 is an enlarged partial section through the control valve. The control valve 21 has as its body a four way connection provided with a central chamber designed to contain the plug 21^a provided with a valve stem 27. In Fig. 4 the plug 21^a is shown in position as are also the valve body connections for the intake pipe 20 on the right, the exhaust pipe 24 on the left, the pipe 22 to the top of the cylinder and a conduit 23 to the base of the cylinder. In Fig. 5 the valve 21 is shown with a valve stem 27 and plug 21^a in position. As shown in the drawings the plug is formed with a taper to allow for wear and insure a perfect fit in the valve chamber. A suitable spring 21^b is provided to insure a constant pressure against the plug body and a spring center 21^c operates to apply this pressure at the center of the plug end through its point 21^d and corresponding depression in the plug end. A plug nut cap 21^e serves to inclose the parts of the valve 21 and hold this spring under slight compression. This spring is sufficiently light to permit the turning of the plug by means of the grip 29 on the outer end of the lever 25. As shown in Fig. 4 fluid pressure coming in through pipe 20 is directed by the valve to pipe 23 and the base of the cylinder, thereby operating to raise the piston and the plow. At the same time the other side of the plug is open to allow the fluid being forced from the top of the cylinder to exhaust from pipe

22 out through discharge pipe 24. In this position the valve stem 27 and slotted socket 31 are in their vertical positions. A quarter turn counter clockwise will reverse the direction of the power to the top of the cylinder and connect the bottom of the cylinder with the outlet pipe. In this latter position the slotted socket 31 is in a horizontal plane.

By turning the motor on its support 6 by the operating lever 25, Fig. 3, and a 90° turn of the control grip 29 the whole operation of swinging the plow 17 into the screen 2, turning the power to the top of the piston for the downward cutting stroke, controlling the speed of the descent, reversing the power to the bottom of the piston for the upward stroke and swinging the plow away from the screen can be performed with one hand, leaving the other free to control the speed of the centrifugal.

The locking of the apparatus against accidental turning or reversing of power is a novel feature and is accomplished by the co-operation of the control lever 25 and a latch formed in the support 6. When the lever is swung to one side until stopped by the lug 32, Fig. 3, the plow 17 being removed from the screen 2, the lever is in position to drop behind the latch 33 in the support 6, Figs. 1 and 3. But before the lever can be dropped the power must be turned to the bottom of the piston which movement brings the slotted socket 31 in the valve stem connection to a vertical position. In this position only can the lever 25 be lowered behind the latch 33. When the lever 25 is in its lowest position, Fig. 1, the valve stem extension 30 with a slotted socket 31 drops below the center of the valve stem proper 27, rendering the connection inoperative, due to the difference in turning centers, thus locking the power to the bottom of the piston and thereby preventing the accidental operation of the plow.

From the foregoing it will be observed that the invention provides a construction permitting the plow or paddle to swing with the screen of the centrifugal minimizing the wear on the screen, the pressure of the paddle against the screen being proportional to that exerted by the hand of the operator on the lever. Further it will be noted that upon the completion of the downward cutting stroke with the plow swung clear of the screen and the power locked to the bottom of the piston the operator may safely leave the apparatus without waiting for the plow to reach the upper position. In addition to these advantages over former constructions the invention provides a machine performing numerous operations all of which are under the direction of a single control device designed to be operated by one hand leaving the other free to attend to the manipulation of the centrifugal clutch.

Changes in the design, the respective to-

cation of the parts, and means and material for conveying the source of power may be made without departing from the scope of the invention.

5. What I claim is:

1. In a machine of the character described, means for cleaning the inner surface of a centrifugal machine, means for adjusting the elevation of said cleaning means, means for adjusting the horizontal position of said cleaning means, and a single control medium for regulating both of said adjusting means.
2. In a machine of the character described, the combination of the casing of a centrifugal machine and the basket thereof, means for cleaning said basket, means for adjusting the elevation of said cleaning means, means for adjusting the horizontal position of the cleaning means relative to said basket, and a single control medium for regulating both said vertical and horizontal adjusting means.
3. In a machine of the character described, the combination of the casing of a centrifugal machine and the basket thereof, means for cleaning said basket, means for adjusting the elevation of said cleaning means, means for adjusting the horizontal position of said cleaning means relative to said basket, a single control medium for regulating both said vertical and horizontal adjusting means, and a support upon which said adjusting and controlling means is mounted, said support providing bearings for one adjusting means and a limit latch for said control means.
4. In a machine of the character described, the combination of the casing of a centrifugal machine, the basket thereof, a support, a motor mounted on said support, a plow for cleaning said basket connected to said motor, and a single control device for operating the motor to raise and lower the plow and change the horizontal position of the plow relative to said basket.
5. In a machine of the character described, the combination of the casing of a centrifugal machine, the basket thereof, a support, a motor mounted on said support provided with a reciprocating piston rod, one end of which projects beyond the motor, a plow for cleaning said basket mounted on said projecting rod, and control means for adjusting the movements of said reciprocating piston, and control means for adjusting the horizontal position of the plow relative to said basket.
6. In a machine of the character described, the combination of the casing of a centrifugal machine, the basket thereof, a support mounted on said casing, a reciprocating motor mounted on said support provided with a projecting piston rod, a plow for cleaning said basket mounted on said projecting piston rod, and a single control

device for regulating the movement of said motor and piston rod and rotating said motor on its support.

7. In a machine of the character described, the combination of the casing of a centrifugal machine, the basket thereof, a support mounted on said casing, a reciprocating motor mounted on said support provided with a projecting piston rod, a plow for cleaning said basket mounted on said projecting piston rod, a single control device for regulating the movement of said motor and piston rod and rotating said motor on said support, a limit stop for said rotary movement, and a latch for locking said control device in one extreme position.

8. In a machine of the character described, the combination in a centrifugal machine of a casing and its basket, a support, a motor on said support, a plow for cleaning said centrifugal basket connected to said motor, and a single control device regulating the movement of said motor to raise and lower said plow and regulate the movement of the plow in its horizontal plane relative to said basket.

9. In a machine of the character described, the combination of a centrifugal machine and an unloader, comprising a support, a motor mounted on said support, a plow connected to said motor, and a single control device to regulate said motor and the vertical and horizontal positions of said plow.

10. An unloading mechanism for centrifugal machines, comprising a support, a motor mounted on said support, a plow connected to said motor to be moved thereby, and single control means for regulating the movement of said plow in its vertical and horizontal planes.

11. An unloading mechanism for centrifugal machines, comprising a support, a motor mounted on said support, a plow connected with said motor, single control means for regulating the movement of said plow in its vertical and horizontal planes, a limit stop and a latch for locking said control means when the plow is in an inoperative position.

12. An unloading mechanism for centrifugal machines, comprising a support, a motor mounted on said support, a plow connected with said motor, single control means for regulating the operation of said motor and the movement of the plow in its vertical and horizontal planes, the plow being fixed against movement toward and from said motor and non-rotatable relative thereto, the distance between the motor and the plow varying under the regulation of the said control means.

13. An unloading mechanism for centrifugal machines, comprising a support, a reciprocating motor mounted on said support, a piston rod, means to prevent the rotation of

said piston rod relative to said motor, a plow connected to said piston rod, single control means for regulating the operation of the motor and the movement of the plow in its vertical and horizontal planes.

14. An unloading mechanism for centrifugal machines, comprising a support, a reciprocating motor mounted on said support, a piston rod, means to prevent the rotation of said piston rod relative to said motor, a plow connected to said piston rod, and control means for regulating the operation of the motor and turning said motor upon said support.
15. An unloading mechanism for centrifugal machines, comprising a support, a reciprocating motor mounted on said support to turn on its vertical axis, a piston rod, means to prevent the rotation of said piston rod relative to said motor, a plow connected to said piston rod, and control means for regulating the operation of said motor and turning said motor about its vertical axis on said support.
16. An unloader mechanism for centrifugal machines, comprising a support, a reciprocating fluid motor mounted on said support to turn on its vertical axis, a piston rod, means to prevent the turning of the piston rod relative to said motor, a plow attached to said piston rod, a four way valve for directing the power to either end of said motor, and a single control device for regulating said four way valve and manually turning said motor on its vertical axis.
17. The combination in a centrifugal machine of a support, a reciprocating motor mounted to rotate on its vertical axis on said support, a piston rod, a cleaning member connected to said piston rod, means to prevent the rotation of said piston rod relative to said motor, and single control means for regulating the operation of said motor and turning the same on its vertical axis.
18. In combination with a centrifugal machine, a support, a reciprocating motor mounted to rotate on its vertical axis on said support, a piston rod, a cleaning member connected to said rod, and single control means for regulating the operation of said motor and turning the same on its vertical axis, said support being provided with a limit stop and latch for locking said control means.
19. In a machine of the character described, a revoluble centrifugal member, a support, a motor mounted on said support to rotate on the vertical axis of said motor, a cleaning member arranged to rotate with said motor, and single control means for regulating the operation of said motor and turning the same on its vertical axis.
20. In a machine of the character described, a centrifugal member, a support, a motor mounted on said support to rotate on

the vertical axis of said motor, single control means for regulating the operation of said motor and turning the same on its vertical axis, and a limit stop and latch for rendering said control device inoperative.

21. An unloading mechanism for centrifugal machines comprising a support, a fluid motor movably mounted on said support, a cleaning member connected to said motor to be actuated thereby, a distributor member for directing the application of power to said motor, and a control device for said distributor member comprising a two-part stem adapted to rotate on its axis when in the operative position, and a slotted socket on one of said parts constituting a receiving member, the other of said parts having a projecting end for engagement with said slotted socket, the said control device being in the operative position when the said two-parts are in alinement and said projecting end is in said socket and in the inoperative position when the parts are not in alinement and the projecting end is not in said socket.

22. An unloading mechanism for centrifugal machines comprising a support, a fluid motor mounted for movement on said support, a cleaning member connected to said motor to be actuated thereby, a distributor member for directing the application of power to said motor, and a control device for said distributor member comprising a hollow lever attached to said motor for moving said motor on said support, a two part stem operating within said lever to adjust said distributor member, and a slotted connection between the said two-parts, said control device being in the operative position when said two-parts are in alinement and forming a single control element for the operation of said distributor member and the movement of said fluid motor on said support.

23. An unloading mechanism for centrifugal machines comprising a support, a fluid motor mounted for movement on said support, a cleaning member connected to said motor to be actuated thereby, a distributor member for directing the application of power to said motor, and a control device for said distributor member comprising a hollow lever attached to said motor for moving said motor on said support, a two part stem operating within said lever to adjust said distributor member, a slotted connection between the two-parts of said stem, and a limit stop and latch for rendering said control lever inoperative when the respective turning centers and the slotted connection of the two-parts of said stem are out of alinement.

24. The combination in a centrifugal machine of a support, a fluid motor rotatably mounted upon said support, a cleaning

member connected to said motor, and a device for controlling the application of power to said motor, and rotating said motor, and a lock for preventing the rotation of said motor when the control device is in a specified position.

25. In an unloading mechanism for centrifugal machines, a support, a fluid motor rotatably mounted on said support, a cleaning member connected to said motor, and a unitary control device rotatable on its own axis for controlling the application of power to said motor and rigidly connected to said motor for manually turning the same on said support.

26. In an unloading mechanism for centrifugal machines, a support, a motor rotatably mounted on said support, a cleaning member connected to said motor, and a unitary control device rotatable on its own ²⁰ axis for controlling the application of power to said motor and rigidly connected to said motor for manually turning the same on said support.

In testimony whereof I affix my signature ²⁵ in presence of two witnesses.

CLARENCE WHITE.
